(57) **CLAIM**

The ornamental design for a hair dryer, as shown and described.

DESCRIPTION

FIG. 1 is a front and bottom perspective view of a hair dryer design showing my new design.

FIG. 2 is a rear and top perspective view of a hair dryer.

FIG. 3 is a front view of a hair dryer, shown enlarged in scale.

FIG. 4 is a rear view of a hair dryer, shown enlarged in scale.

FIG. 5 is a left side view of a hair dryer.

FIG. 6 is a right side view of a hair dryer.

FIG. 7 is a top view of a hair dryer; and,

FIG. 8 is a bottom view of a hair dryer.

Any shading is not features of the design but is utilized to illustrate the surface contours of the hair dryer design in the drawings.

The broken lines in FIG. 3 depict portions of the hair dryer that form no part of the claimed design.
